Application February 9, 1955, Serial No. 487,170

3 Claims. (Cl. 250—27)

The present invention relates to electronic time delay
relays.It is an object of the present invention, to provide an
electronic time delay relay wherein the time delay is
practically not dependent on variations of feed voltage
and tube emission.With this and other objects in view which will become
apparent in the following detailed description, the present
invention will be clearly understood in connection
with the accompanying drawing, in which:

The only figure is a schematic circuit diagram illustrating a preferred embodiment of the present invention.

Referring now to the drawing, the device comprises a
dual stability tube circuit 1, with some respects similar to
a flip-flop circuit. Contrary to the known circuit, how-
ever, the cathode voltages of tubes 2 and 3 differ from
one another. The cathode of tube 2 receives a positive
bias voltage 2', smaller than the operational voltage of
the tube circuit. Its cathode being biased, the control
voltage of tube 2 may be positive or negative relative
to the cathode. The cathode of tube 3 being not biased,
the output voltage of the relay, may be picked up across
the grid and the grounded cathode of tube 3, and be
used for example to control a subsequent stage.In neutral state, the grid of an electron tube 4, connected
to the tube circuit 1 through a resistor 6, has the
same potential as the cathode, i.e. the tube 4 is unblocked.
Its inner resistance is in parallel to a capacitor 5 connected
between resistor 6 and zero potential. With
proper choice of the resistors 6, 7 and 13, the voltage
applied to the grid of tube 2 is lower than the voltage
2' applied to the cathode of tube 2. This grid, therefore,
is negatively biased and tube 2 is blocked. The poten-
tiometer, formed by the anode resistor 10 of tube 2 and
two resistors 11 and 12, connected across the operational
voltage and the negative grid bias voltage 3' is chosen
such, that with blocked tube 2, i.e. when no anode current
flows in resistor 10, the voltage picked up at the junction
point of resistors 11 and 12 and lead to the grid of tube 3
is with certainty such, that this latter tube is unblocked.
In neutral state tubes 3 and 4 are unblocked and tube 2
is blocked.If now tube 4 is blocked in order to energize the relay,
the voltage across capacitor 5 increases. In accordance
with the time constant of the RC-circuit formed by the
network of resistors and condenser 5, the grid voltage
of tube 2 rises until anode current starts to flow. The
voltage drop across resistor 10 of potentiometer 10,
11, 12 increasing thereby, the grid voltage of tube 2
decreases. Hereby also the anode current in resistors 8,
9 in the anode circuit decreases, while the voltage at
the junction point of resistors 8, 9, and thereby the grid
voltage of tube 2 rises. This phenomenon, independently
of further loading capacitor 5, continues until grid cur-
rent in tube 2 starts to flow. Since anode current then
starts to flow in resistor 10, the negative grid voltage
of tube 3 becomes as high as to completely block thistube. In state of operation, therefore, tubes 3 and 4
are blocked and tube 2 is unblocked.By proper choice of resistors 6 and 7, the transition
from one state into the other can be accomplished in a
relatively short time. The voltage leaps caused hereby
at the anodes of tubes 2 and 3 can be picked up on the
terminals 14 and 15, respectively, and, after taking the
derivatives, can be used as steering pulses.When tube 4 is again made to be unblocked, capacitor
5 discharges over the anode-cathode path of tube 4. As
soon as the grid of tube 2 becomes negative with respect
to the cathode, tubes 2 and 3 fall back again into the
starting condition.The time needed for this can be made very short com-
pared with the time of delay.

The time of delay can be found from

$$t = CR \cdot \ln \frac{1}{1 - \frac{U_k - U_b}{U}}$$

wherein R is the equivalent resistance corresponding to
the network, and U is the equivalent voltage across
capacitor 5 with the capacity C. U_b is the grid bias
voltage of the tube, in which the anode current is fallen
down to a negligible small value. With constant capacity
and constant resistance the time of delay t depends on
the ratio

$$\frac{U_k - U_b}{U}$$

wherein U is practically proportional to the operational
voltage. With triodes applied U_b depends on the operational
voltage. In order to keep as small as possible
the influence of a change of U_b which also occurs with
a decrease of emission, U_k must be possibly large with
respect to U_b. For the same reason, the moment of
transition shall be within the steep slope of the curve of
charge against time of the capacitor, i.e. when

$$\ln \frac{1}{1 - \frac{U_k - U_b}{U}} \leq 1$$

Since with variations of the primary voltage of the
power supply the ratio of the operational voltage and 2'
remains constant, the time delay is practically not influ-
enced thereby. Measurements with a tentative device
have proved that with a 10% change of the supply volt-
age the change of the time delay is smaller than 1%.
Hereby in most cases stabilization of supply voltage
becomes unnecessary whereby considerable savings can be
obtained. Any number of electronic time delay relays
according to the invention having different values of
time delay may be switched in series by connecting the
grid of tube 4 to terminal 16 of tube 3 of the preceding
relay. Herewith, in consequence of the load dependency
of normal, not stabilized circuit devices, also the ratio of
the operational voltages and that of 2' is changed. There-
fore it becomes necessary to choose the electric values of
each stage according to the ratio of voltage as they
exist after the response of the preceding stage, whereby,
also in this case, variations of the feed voltage remain
without influence.The time delay of my invention differs from devices
of the prior art, besides by other characteristics, by a
dual stability tube circuit comprising two electron tubes,
wherein the cathode of the tube following the input is
on a positive potential and the grid of this tube is con-
nected to one electrode of a capacitor in parallel with
a switching device, for example an electron tube, the
other capacitor electrode being grounded; the cathode of
the other tube of said circuit being grounded such, that
an output voltage may be picked up across the grid

and the cathode of this tube and be used, for example, for controlling a subsequent stage. The switching device in parallel with the capacitor is operated by a grounded control voltage source.

The time delay according to my invention is advantageous as compared with time delay relays using glow-discharge lamps or thyratrons, in so far, as it is less dependent on temperature changes.

I have described a preferred embodiment of my invention, but it is understood that this disclosure is for the purpose of illustration and that various omissions or changes in arrangements of parts, as well as the substitution of equivalent elements for those, herein shown and described may be made without departing from the spirit and scope of the invention as set forth in the appended claims.

I claim:

1. An electronic time delay apparatus comprising a flip-flop circuit including a first electron tube and a second electron tube, a source of anode potential, resistor circuit means connecting the anodes of said tubes to said source of potential, a direct current connection from the control grid of each tube to the anode resistive circuit of the other tube applying a high positive potential to the control grid of said second tube from the plate of said first tube when said first tube is non-conducting, means for maintaining the cathode of the first electron tube at a considerable positive potential yet lower than the potential of the anode of said first electron tube, and maintaining the cathode of the second tube at a much lower potential than that of the cathode of said first tube, a switching circuit comprising a third electron tube, a capacitor connected between the cathode and the anode of said third tube, means including a resistor for applying a charging potential to the anode of said third tube and said capacitor, a direct current coupling from the control grid of said first tube of said flip-flop circuit to the anode of said third tube, means for maintaining said first tube non-conductive and said second and third tubes normally in a conductive state, and means for applying control potentials to the control electrode of said third tube for rendering it non-conductive and thereby applying potential to said control grid of the first tube which renders it conductive and causes said third tube to become non-conductive, and means for obtaining output voltages from said flip-flop circuit which are delayed with respect to said control potentials.

2. An electronic time delay apparatus comprising a flip-flop circuit including a first electron tube and a second electron tube, a source of anode potential, resistor means connecting the anodes of said tubes to said source of potential, direct current connection from the control grid of each tube to the anode of the other of said tubes, means for maintaining the cathode of said first of said electron tubes at a relatively high positive potential and

the cathode of said second tube at a relatively low potential, a switching circuit comprising a third electron tube, a capacitor connected between the cathode and the anode of said third tube, means including a resistor for applying a charging potential to the anode of said third tube and the capacitor, a direct current resistive coupling from the control grid of said first tube of the flip-flop circuit to the anode of said third tube, means for maintaining said first tube non-conductive and said second and third tubes normally in the conductive state, and means for applying control potentials to the control electrode of said third tube for rendering it non-conductive and thereby applying a potential to the control grid of said first tube which renders it conductive and causes the third tube to become non-conductive, and means for obtaining output voltages from said flip-flop circuit which are delayed with respect to the control potentials.

3. An electronic time delay apparatus comprising a flip-flop circuit including a first electron tube and a second electron tube, a source of anode potential, resistor means connecting the anodes of said tubes to said source of potential, direct current connection from the control grid of each tube to the anode of the other of said tubes, means for maintaining the cathode of the first of said electron tubes at a considerable positive potential relative to but lower than that of the anode potential, a switching circuit comprising a third electron tube, a capacitor connected between the cathode and the anode of said third tube, the cathodes of the second and third tubes being at zero potential, means including a resistor for applying a charging potential to the anode of the third tube and the capacitor, a direct current resistive coupling from the control grid of said first tube of said flip-flop circuit to the anode of the third tube, means for maintaining said first tube non-conductive and said second and third tubes normally in the conductive state, and means for applying control potentials to the control electrode of said third tube for rendering it non-conductive and thereby applying a potential to the control grid of said first tube which renders it conductive and causes the second tube to become non-conductive, and means for obtaining output voltages from said flip-flop circuit which are delayed relative to the control potentials.
